UNITED STATES PATENT OFFICE.

STRICKLAND L. KNEASS, OF PHILADELPHIA, PENNSYLVANIA, ASSIGNEE TO WILLIAM SELLERS AND COMPANY, INCORPORATED, OF PHILADELPHIA, PENNSYLVANIA, A CORPORATION OF PENNSYLVANIA.

INJECTOR.

1,318,089.

Specification of Letters Patent. Patented Oct. 7, 1919.

Application filed October 23, 1918. Serial No. 259,384.

To all whom it may concern:

Be it known that I, STRICKLAND L. KNEASS, a citizen of the United States, residing at Philadelphia, county of Philadelphia, and 5 State of Pennsylvania, have invented a new and useful Improvement in Injectors, of which the following is a full, clear, and exact description, reference being had to the accompanying drawings, which form a part of 10 this specification.

My invention relates to injectors adapted for use in feeding boilers, and particularly to such injectors as applied to locomotives, wherein, owing to lack of space in the cab, 15 the injector is usually positioned outside the cab and therefore is not within the range of observation of the engine driver. From a variety of causes, the injector may fail to work properly. Thus, operating conditions 20 may be interrupted by a cessation of the supply of water or steam, or by failure to maintain the relative proportions of water and steam within the limiting range of maximum and minimum capacities of the injector. 25 These abnormal conditions produce different results, such as failure of the injector to receive a proper supply of water, wastage of water at the overflow, and blowing back of steam through the suction pipe, all of which 30 it is important to avoid, or at least to promptly correct.

The object of my invention is to provide an indicator, positioned within the cab, and readily observable, which will be operated 35 by the correct functioning of the jet but which will cease to be so operated in the event of any abnormal operation, or any failure in operation, of the injector, and which will also, by operating in a differential 40 manner, show to the engine driver when the minimum capacity of the injector has been reached.

To particularize: During the operation of the injector, if the relative proportions of 45 water and steam are within the limiting range of maximum and minimum capacities, there will be a partial vacuum within certain parts of the combining tube, which may even extend to the minimum diameter of the delivery tube. When the combining tube is provided, as is usual, with an outlet opening into an inclosing chamber sealed against admission of air, the internal vacuum will be communicated to this chamber. The par-

tial vacuum or absolute pressure within this 55 chamber approaches atmospheric pressure as the maximum and minimum limits of proportion of water to steam are reached. At the maximum capacity of the injector, the 60 vacuum within the chamber may be only two or three inches; at the mean capacity, it may reach twenty inches. When the injector is operating at the minimum capacity, the least amount of water is admitted which in combination with the entering steam will produce 65 a continuous jet through the delivery tube without discharge of steam or water at the overflow opening from the body of the injector; under which condition the equilibrium or pressure condition of the jet while 70 passing an opening of the combining tube is unstable or variable, the inner pressure fluctuating from three or four inches of vacuum to or above atmospheric pressure. If a supply of water is admitted above the 75 maximum capacity of the injector, or if the temperature of the supply water be raised to the limit, or if the supply of steam or water is interrupted, the injector will waste water or steam at the overflow. Whenever 80 there is wastage at the overflow, the pressure within the inclosing chamber must be equal to or above that of the atmosphere.

In my invention I utilize the partial 85 vacuum within the combining tube of the injector, or within a containing chamber, to move the indicator away from its normal position when the injector is not in use and take advantage of the described variations 90 in the partial vacuum or absolute pressure, within the combining tube of the injector or within a containing chamber, which accompany variations in the supply of water and steam to the injector and in the temperature 95 of the supply water, and which also coincide with wastage at the overflow, and utilize such variations, when they exceed the normal limits, to either permit the return of the indicator to normal position or cause it 100 to vibrate back and forth, as hereinafter described.

My invention is also advantageously applied to lifting injectors placed in the cab of a locomotive or even for stationary service when the overflow opening from the body 105 of the injector is close-coupled so that the waste of water or steam cannot be observed by the operator.

One preferred embodiment of my invention is illustrated in the accompanying drawings, wherein—

Figure 1 is a vertical sectional view of an injector with my invention applied thereto.

Fig. 2 is a sectional view of the casing containing the overflow valve.

The injector being of a well-known type, only the principal parts thereof will be referred to in the description.

Within the body *a* is the combining tube *b*, the steam nozzle *c*, the delivery tube *d*, and a chamber *e* communicating with the lower overflow *x* of the combining tube. *f* is an inlet for steam; admission of steam being controlled by a valve, not shown, operable by the engine driver. *g* is the outlet from the injector to the boiler.

A valve casing is located alongside and forms part of the injector body. Casing *i* contains an opening *j* for admission of water from the supply tank and a valve *k* coöperating with a valve seat to control the admission of water from the supply through the casing *i* to the injector proper. The spindle *m* of the valve is threaded in a stuffing box and is turnable, through mechanism, not shown, and operable from the cab, to regulate the supply of water to the injector.

Located alongside and forming part of the injector body is a casing containing a pipe *n* opening into the chamber *e* and provided with a valve seat, a waste pipe *o*, and a valve *p* seated on said seat. The valve *p* opens to permit the discharge of water or steam in case the supply of water is above that of the maximum capacity, or below that of the minimum capacity, or above the limiting temperature of the injector; and closes to seal against admission of air and maintain the operating vacuum in the overflow chamber under normal operating conditions. The valve *p* operates automatically, but its opening may, at will, be governed by the screw stem *q*, which is turnable, through mechanism not shown, by the driver.

Without modifying the construction of the injector, I have arranged for indicating to the driver predetermined variations in absolute pressure of the moving jet by connecting the overflow chamber *e* (in which, as well as in the combining tube *b*, such variations occur), by means of a pipe *r*, with a vertically positioned cylinder *s* containing a loosely sliding piston *t*. The pipe *r* communicates with the upper end of the cylinder *s*, the lower end of the cylinder having threaded therein a head *u*, through which the stem *v* of the piston extends and upon which the head of the piston seats when the pressure within the cylinder balances or exceeds the pressure of the atmosphere constantly operating upon the lower face of the piston. The piston heads seats with a tight

joint at each end of its stroke, preventing inflow of air or outflow of steam or water at its terminal positions.

When admission of water to the combining tube is permitted by opening the regulating valve *k*, the pressure within the chamber *e* may be equal to, or above, the atmospheric pressure, and in such case, the position of the indicator *t* will not be affected and will be visible to the operator at the lowest position. When the steam admission valve is gradually opened, lifting the water supply or forcing a flow of water from the overflow, there will be a plenum within the chamber *e* and the indicator *t* will remain seated at the lower end of the stroke. When the steam valve is opened wide and the correct adjustment of water and steam is obtained, there will be a partial vacuum within the chamber *e*, which will seat the overflow pipe *p*, sealing the chamber *e* against admission of air. The partial vacuum will be communicated to the cylinder *s* and atmospheric pressure will lift the piston against its upper seat, thus causing the projecting end of the stem of piston *t* to disappear. This will indicate to the engine driver that normal conditions exist within the injector and particularly that there is no waste at the overflow.

If normal operating conditions be interrupted either by a cessation of supply of water or steam, the partial vacuum within the inclosing chamber *e* will be lost and the change of condition will be communicated to the cylinder *s*; gravity will cause the piston *t* to drop, exhibiting to the operator the projecting lower end of the piston stem and indicating that an abnormal condition exists. When the supply of water or steam is resumed, if the injector be of the type that restarts automatically, as is the injector illustrated, a partial vacuum will again be obtained within the combining tube and the indicator will return to its raised position, indicating that the injector is feeding the boiler without waste.

It is frequently desirable to throttle down the supply of water close to the minimum capacity of the injector, which is obviously difficult because of the likelihood of reducing the water supply below the minimum capacity. If this should occur with an injector which is not capable of restarting automatically, the continuity of the jet will be broken, and steam will discharge through the water-admission valve into the supply pipe with a tendency to overheat the supply above the ability of the injector to use it. In any case, the continuity of the jet may be partially or completely destroyed and steam and hot water discharge from the water pipe, with danger of injury to attendant, employee or passenger, standing near the overflow pipe. As the supply of water is

reduced, the vacuum within chamber *e* increases until it reaches perhaps twenty inches. As the ratio of water to steam drops to the lowest point at which the jet will 5 operate, the vacuum drops suddenly. Thereafter, slight variations in the pressure of water and steam and the condition of the jet cause frequent and rapid changes in the pressure within the chamber *e*, the fluctuations being from below to above atmospheric pressure. These fluctuations are communicated to the indicator and produce a condition of unstable equilibrium in the position of the piston *t*, showing to the observer that the exact minimum capacity of 10 the injector has been reached.

It is obvious that the invention is not limited to the specific embodiment thereof herein specifically described, as the skilled 20 engineer, familiar with the inventive conception inherent therein, can readily apply or devise modifications operating on the same principle.

A further advantage of this form of indicator which is sealed against overflow when the pressure within the combining tube and inclosing overflow chamber of the injector exceeds that of the atmosphere is 25 that no steam or water will issue from the indicator when it is necessary to heat the water supply in winter, requiring the closing of the waste valve *p* by means of the stem *q* so that the steam entering through the steam nozzle will flow back through suction inlet *j* into the tank.

It will be observed that in the embodiment of the invention disclosed, the indicator, while the injector is not operating, will assume the same position that it assumes 40 when, during the operation of the indicator, abnormal conditions arise, and that the movement of the indicator away from this position is effected only by the proper functioning of the jet. In other words, the indicator is moved away from its normal position by the proper functioning of the jet. When the operation of the injector is started, the indicator does not recede from its normal 45 position until the jet is properly functioning, and it resumes its normal position of indication or alarm only when the jet functions abnormally or, by the stoppage of the injector, ceases to function altogether.

Having now fully described my invention, 50 what I claim and desire to protect by Letters Patent is:

1. The combination with an injector, of an indicator, said parts comprising provisions constructed and arranged to cause the indicator to be operable from its normal position by the correct functioning of the jet.

2. The combination with an injector including the combining tube thereof having 55 an opening, of an injector indicator com-

municating with said opening, said parts comprising provisions constructed and arranged to cause the indicator to be operable by the passage of the jet.

3. The combination with an injector including the combining tube thereof having an opening, of an injector indicator communicating with said opening, said parts comprising provisions constructed and arranged to cause the indicator to be operable 70 by the correct functioning of the jet.

4. The combination, with an injector including a delivery tube and a combining tube having a water entrance and an opening between the water entrance to the combining tube and the minimum diameter of the delivery tube, of an injector indicator, said parts comprising provisions constructed and arranged to cause the indicator to be operable 75 by the passage of the jet of water and combined steam across said opening.

5. The combination, with an injector including a combining tube and an overflow chamber containing an opening of the combining tube, of an injector indicator comprising 80 a piston, and means for communicating a change of pressure in the overflow chamber to a face of the piston.

6. The combination, with an injector having an opening between the water inlet and the delivery end, of a pneumatically operable indicator, and means affording pneumatic communication through said opening between the interior of the injector and the indicator, said indicator being operable in 95 one direction by atmospheric pressure working in conjunction with a partial vacuum within the injector and in the other direction against said atmospheric pressure by a predetermined rise in absolute pressure 100 within the injector.

7. The combination, with an injector including the combining tube and a chamber communicating with an outlet from the combining tube, of an indicator sealed against 110 fluid admission and outflow, said parts comprising provisions constructed and arranged to cause the indicator to be operable, by reduction of absolute pressure in said chamber, to indicate the correct functioning of the 115 injector.

8. The combination, with an injector including its combining tube and a chamber communicating with an opening of the combining tube, of an indicator, said parts comprising provisions constructed and arranged to cause the indicator to be operable by variations of absolute pressure in said chamber to record the point of regulation for minimum capacity of the injector.

9. The combination, with an injector including its overflow chamber, of an indicator, said indicator comprising means operable at the limiting point of regulation for the minimum capacity of the injector, said 125 130

means including a pneumatically operable device subjected to oppositely acting atmospheric pressure outside the injector and absolute pressure within the overflow chamber.

10. In an injector, the combination, with the combining tube, the main water entrance thereto, the delivery tube and a chamber inclosing the combining tube and communicat-
10 ing therewith between said main water en-

trance of the combining tube and the delivery tube, of an indicator operable in one direction by the atmosphere in conjunction with a partial vacuum within said chamber and in the other direction by a predetermined absolute pressure within said chamber. 15

In testimony of which invention I have hereunto set my hand, at Philadelphia, Penna., on this 21st day of October, 1918.

STRICKLAND L. KNEASS.
